UNITED STATES PATENT OFFICE.

NICHOLAS A. STEFFEN, OF NEW VIENNA, IOWA.

LATCH.

Application filed February 24, 1922. Serial No. 538,862.

To all whom it may concern:

Be it known that I, NICHOLAS A. STEFFEN, a citizen of the United States, residing at New Vienna, in the county of Dubuque and State of Iowa, have invented certain new and useful Improvements in Latches, of which the following is a specification.

This invention relates to latches and has for its object the provision of a cheap, simple and efficient device which may be easily applied to the doors of barns, animal pens, or similar structures, and which will effectually hold the door in closed position but permit its ready opening from the outside whereby access may be had to animals confined in a pen, for instance, but escape of the animals from the pen will be prevented. The invention is illustrated in the accompanying drawings and will be hereinafter fully set forth.

In the drawings—

Figure 1 is an elevation of my improved latch showing the same in applied position;

Fig. 2 is an end elevation of the same. In the drawings, the reference numeral 1 indicates a door and 2 indicates a portion of a door frame. In carrying out the invention, I secure to the outer side of the door a latch pin consisting of a flat base plate 3 provided with spaced vertical slots 4, through which screws or similar fastening devices 5 are inserted into the door, and a cylindrical terminal pin or locking arm 6 which is adapted to ride into engagement with a keeper provided upon the door frame. The keeper consists of a bracket presenting a shelf 7 and a bracing portion 8 extending downwardly and inwardly from the outer end of the shelf and terminating in a flat perforated lip 9 through which a fastening screw 10 may be inserted into the door frame. Rising from the inner end of the shelf 7 is a back plate 11 which is preferably integral with the shelf and is perforated to permit the insertion of a securing screw 12 into the door frame whereby the bracket will be firmly secured in place.

At the upper end of the base plate is provided a forwardly projecting arm 13 which is tapered and doubled upon itself as it leaves the back plate so as to provide the inverted U-shaped terminal 14 within which the dog or keeper pin 15 is pivoted. This dog 15 is longer than the distance between its pivot 16 and the shelf 7 so that normally the dog will assume a rearwardly or in-

wardly inclined position, as shown clearly in Fig. 2, with its lower end resting upon the shelf but spaced forwardly from the back plate 11. The free end of the dog is 60 also expanded laterally, as shown at 17, whereby in its operative position it will have an extended engagement with the latch pin 6.

It is thought the operation of the device 65 will be readily understood from the foregoing description, taken in connection with the accompanying drawings. The bracket is secured to the door frame adjacent the edge thereof, as described and shown, and the 70 latch is secured to the door and adjusted vertically so that, when the door is closed, the latch pin 6 will project over the shelf 7 close to the same but without bearing thereon, the vertical slots 4 permitting the 75 latch to be adjusted so that it will readily clear the shelf in the closing movement of the door and may also be set so as to compensate for sagging of the door. As indicated by the dotted lines in Fig. 2, as the 80 door is closed the pin 6 will ride against and under the dog which will be thereby swung upwardly so as to clear the pin and as soon as the pin has reached a position back of the free end of the dog, which will 85 occur when the door is fully closed, the dog will, through its own weight, return to its position and will be disposed in front of the pin so that the door will be effectually held in the closed position. Obviously, any 90 outward movement of the door under pressure from the inside will be arrested by the engagement of the dog with the pin, but if it be desired to open the door from the outside, a slight pressure upon the under 95 or forward side of the dog will swing it upwardly so that the pin will be cleared and the door may then be opened.

My device is obviously simple and inexpensive and may be readily applied in operative position by an unskilled person.

Having thus described the invention, what is claimed as new is:

A door fastener comprising a latch consisting of a base plate adapted to be secured against the outer side of a door, and a rigid cylindrical pin projecting from the end of said base plate beyond the edge of the door, a bracket to be secured to a door frame and including a flat approximately horizontal 105 shelf, a brace extending downwardly and inwardly from the outer end of the shelf,

a flat back plate rising from the rear edge of the shelf and an overhanging arm projecting forwardly from the upper end of said back plate, said arm being folded longitudinally whereby to present an inverted U-shaped terminal at its front end, and a dog pivotally hung at its upper end within said U-shaped terminal and held against lateral movement thereby and extending

downwardly and rearwardly from the pivot, 10 its free end being square and normally resting upon the shelf and spaced from the back plate whereby the cylindrical pin may ride upon the shelf and be firmly retained between the square end of the dog and the 15 back plate.

In testimony whereof I affix my signature.
NICHOLAS A. STEFFEN. [L. S.]
